BELA L. CHURCHILL AND GEORGE Z. VANDERSLICE, OF PHILIPSBURG, PENNSYLVANIA.

Letters Patent No. 97,602, dated December 7, 1869.

IMPROVEMENT IN DEVICE FOR TURNING LOGS IN SAW-MILLS.

The Schedule referred to in these Letters Patent and making part of the same.

To all whom it may concern:

Be it known that we, BELA L. CHURCHILL and GEORGE Z. VANDERSLICE, of Philipsburg, in the county of Centre, and State of Pennsylvania, have invented certain new and useful Improvements in Saw-Mills; and we do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use our invention, we will proceed to describe it.

Our invention relates to saw-mills; and

It consists in a novel arrangement of devices whereby the action of the carriage, in its backward or return movement, is caused to turn the log, for slabbing and similar operations.

In the drawings—

Figure 1 is a side elevation of our device in operation, and

Figure 2 is a top plan view of the same.

A is the carriage, constructed in the ordinary manner, and provided with the usual dogs or head-blocks B.

C is the saw-log in position on the carriage.

D is an overhead cross-beam, forming part of the frame-work of the mill, and having pivoted to or above it, an arm or lever, E, extending parallel with the line of travel of the carriage, as shown in both figures.

F is a long depending arm or push-bar, attached to the bar E near its middle, and the lower end of which may be engaged in teeth or notches e, made in the carriage for that purpose, so that as the carriage is moved backward, the push-bar will raise the lever E.

As the push-bar does not push squarely under the lever E, but a little from one side, a rope or chain, i, is secured from the end of the lever to the end of the cross-beam, as shown in figs. 1 and 2, to prevent any lateral movement of the lever E.

G is a long rope or chain, attached to the free end of the lever E, and provided, on its lower end, with a strong hook, d.

In operating the device, the carriage being at the end of its forward movement, the end of the push-bar is set into one of the notches in the carriage, and the rope or chain passed around the back end of the log, and the hook driven firmly into it, as shown in figs. 1 and 2. The carriage is then moved backward, causing the push-bar to operate the lever E, which, drawing upon the rope G, turns the log over. When the log is turned the required amount, the push-bar and the hook are disengaged, allowing the log to remain stationary on the carriage, while it finishes its movement.

To the cross-beam we attach a bar, H, having an arm, I, at its end, on which the push-bar is rested when not in operation, so as to be out of the way.

The rope G may be wound in either direction around the log. When wound from the dogs, no devices are necessary to hold the log on the carriage, but when wound toward them, bands or straps may be placed around it to prevent it from rolling off.

Having thus described our invention,

What we claim, is—

1. The combination of the lever E, with the rope or chain G attached thereto, and the push-bar F, with the carriage of a saw-mill, all arranged to operate substantially as described.

2. Turning a log on a saw-mill carriage, by the backward movement of the carriage, in connection with the lever E, rope or chain G, and push-bar F, as set forth.

BELA L. CHURCHILL,
GEORGE Z. VANDERSLICE.
